UNITED STATES PATENT OFFICE

2,519,110

CYLINDER HEAD ASSEMBLY

William M. Carraway, Norfolk, Va.

Application February 17, 1949, Serial No. 76,919

2 Claims. (Cl. 123—41.56)

1

The present invention relates to improvements in cylinder head assemblies and especially for air-cooled gasoline engines in which the cooling is accomplished by force draft air blowing through air ducts across or over radially extending fins.

Heretofore, air-cooled gasoline engines of this type which have been used on machinery and/or equipment, such as mowers and the like, have failed to give long service due to becoming overheated and burning out. It has been discovered by observation and experience that this burning out of this type engine has been caused by an accumulation of trash, leaves, grass, and/or other foreign material accumulating in and/or around the air ducts. The design of the cooling system for air-cooled engines of the prior art is very susceptible to this accumulation of trash which clogs and/or covers the air ducts which in turn decreases the efficiency of the cooling system and in some cases prevents operation of the cooling system as such.

With the conventional type of cylinder head, in order to clear the air ducts of this foreign material it is necessary to dismantle part of the engine assembly to enable the operator to clear the air intake and air exhaust ducts with a wire, or similar object, by digging out as much of the foreign material as possible. This old method has proven very unsatisfactory and impracticable because of the complicated dismantling and reassembling of the engine and its attachments. Moreover, this clogging of the air ducts invariably takes place when the engine is being used in the field remote from a workshop and tool kit. As a result, few operators clean out the air ducts frequently and promptly, and, therefore, many engines are burned out as a direct result of overheating caused by these clogged air ducts.

It is an object of the present invention to overcome this difficulty by providing an improved cylinder head having a cap or cover which can quickly and easily be removed without the use of tools, thus affording easy access to the air ducts and still be readily replaceable while the engine is in actual operation.

A further object of the present invention is to provide an improved cylinder head for eliminating this cause of overheating which can be easily substituted for the conventional type of cylinder head on engines now in service.

Another object of the present invention is to provide an improved cylinder head assembly of this character which is inexpensive to manufac-

2

tire, comprises relatively few parts and the maintenance cost of which is small.

With the foregoing and other objects in view, the invention will be hereinafter more fully described and more particularly pointed out in the appended claims.

In the drawings in which the same parts are denoted by the same reference numerals throughout the several views,

10 Figure 1 is a top plan view of the improved cylinder head assembly.

Figure 2 is a vertical cross sectional view on the line 2—2 of Figure 1.

Figure 3 is a view similar to that of Figure 1 with the cap or cover removed, and

Figure 4 is a bottom plan view of the cap or cover.

Referring more particularly to the drawings, 10 designates a cylinder head having three pairs 20 of bosses 11 and 12, 13 and 14 and 15 and 16 and a boss 17. The cylinder head 10 has tap bolt holes 18 which extend through the bosses 11 to 17 and are adapted to receive the usual tap bolts for attaching the cylinder head to the cylinder block.

As shown in Figure 3, the cylinder head 10 has radially extending spaced apart radiation fins 19 which form therebetween air ducts 20. An air inlet opening 21 communicates with the air ducts 20 for circulating cooling air for the engine. Approximately at its center the cylinder head 10 has a boss 22 which supports a screw threaded stud bolt 23. The stud bolt 23 extends upwardly from the boss 22 and passes through an opening 24 in a cap or cover 25. The stud bolt projects beyond the upper surface of the cap 25 and receives a wing nut 26 for attaching the cap 25 to the cylinder head 10. At one end the cap 25 has a rib 27 which is received by a correspondingly shaped depressed seat 28 formed in the cylinder head 10. The edge of the opposite end of the cap 25 has two spaced apart semi-circular notches 29 and 30 which embrace and interlock, respectively, with the bosses 11 and 12 of the cylinder head 10.

The cap or cover 25 has a downwardly sloping end wall 31 and downwardly sloping side walls 32 and 33 and is of hollow formation so as to accommodate the ribs 19 and boss 22 of the cylinder head 10. The side wall 33 is cut away as at 34 to provide an extension or ear 35 which overlies the receding portion 36 of the cylinder head 10.

In the use of the device, the conventional cylinder head of an engine already in service is re-

moved and the improved cylinder head 10 is secured to the standard engine block by means of the usual tap bolts which are received by the openings 18 in the cylinder head 10. The cover 25 is then placed upon the cylinder head 10 with the stud bolt 23 extending through the opening 24 in the cover 25 and projecting beyond the upper surface thereof. The wing nut 26 is then placed upon the projecting end of the stud bolt 23 and screwed home. When the cover 25 is thus positioned upon the cylinder head 10 the rib 27 of the cover 25 is received by the depressed seat 28 of the cylinder head 10 and the notches 29 and 30 embrace and interlock, respectively, with the bosses 11 and 12 of the cylinder head 10 so that the cover 25 is held against rotation on the cylinder head.

After the engine has been in service long enough for trash and the like to have accumulated in the air ducts 20, the cover 25 can be removed simply by unscrewing the wing nut by hand and lifting the cover 25 from the cylinder head. This removal of the cover can be effected without the use of tools and can be accomplished while the engine is in service in the field remote from a workshop or tool kit. The removal of the cover 25 exposes the air ducts 20 and makes them available to the operator for quickly and thoroughly cleaning out the trash and the like which may have accumulated therein.

Due to the ease and speed with which the cover may be removed and the air ducts cleaned out, the operator is encouraged to frequently remove the foreign material from the air ducts so that overheating and burning out of the engine is prevented. Consequently, the efficiency and the life of the engine is greatly increased.

It is obvious that various changes and modifications may be made in the details of construction and design of the above specifically described embodiment of this invention without departing from the spirit thereof, such changes and modifications being restricted only by the scope of the following claims.

What I claim is:

1. An improved cylinder head assembly comprising a cylinder head having air ducts therein and a pair of spaced apart apertured bosses adjacent one end of the cylinder head adapted to receive tap bolts for securing the cylinder head to the engine block and a depressed seat at the op-

posite end of the cylinder head in opposed relation to the space between said bosses, a threaded stud bolt supported by the cylinder head at substantially the center thereof, a cover for detachable mounting on the cylinder head over the air ducts and having an opening therein through which the stud bolt passes and projects, and a wing nut received by the projecting portion of the stud bolt for detachably securing the cover in position upon the cylinder head, said cover having a pair of spaced apart substantially semicircular notches for interlocking engagement with the bosses of the cylinder head, and having a rib for reception by said seat.

2. An improved cylinder head assembly comprising a cylinder head having air ducts therein and a pair of spaced apart apertured bosses adjacent one end of the cylinder head adapted to receive tap bolts for securing the cylinder head to the engine block, and a depressed seat at the opposite end of the cylinder head, a threaded stud bolt supported by the cylinder head at substantially the center thereof, a cover for detachable mounting on the cylinder head for covering the air ducts and having an opening therein through which the stud bolt passes and projects, and a wing nut received by the projecting portion of the stud bolt for detachably securing the cover in position upon the cylinder head, said cover having a pair of spaced apart substantially semicircular notches on one edge thereof for interlocking engagement with the bosses of the cylinder head, and having a rib on its opposite edge for reception by said seat for centering said cover with respect to said stud bolt and said spaced apart bosses, whereby said stud bolt will be received by said opening in the cover and said notches will receive said spaced apart bosses.

WILLIAM M. CARRAWAY.
